UNITED STATES PATENT OFFICE.

JOHN SOMMER, OF PEORIA, ILLINOIS.

TILE-PLACING ATTACHMENT FOR DITCHING MACHINES.

Application filed September 30, 1922. Serial No. 591,569.

This invention has reference to a tile placing attachment for ditching or excavating machine, which is particularly applicable to wheel type machines.

5 The invention herein, is an improvement upon the structure shown, described and claimed in an application filed by me on June 21, 1920, bearing Serial No. 390,471 which has resulted in Patent Number 1,463,-

10 561.

One of the objects of the present invention is to provide a tile placing attachment for ditching or excavating machines which will facilitate the laying of the tile in any soft 15 ground which is subject to cave-in, and also in ground containing quicksand; whereby, the tile may be pushed into and held in place and a contiguous joint made with the next adjoining tile, and so held, even in the event 20 of cave-in.

The invention has for a further object a tile placing means controlled and actuated by pneumatic pressure means, the fluid pressure for which is supplied by a suitable 25 pump arranged to be operated from the motor mechanism of the excavating machine.

A further object of the invention is to provide an elevating means, associated with the tile placing means, which is adapted to remove from the tile placing attachment, water and slush draining into said attachment, whereby a comparatively dry place may be maintained for the operator, and filling in 30 prevented, until after the tile sections have been properly covered.

That the invention may be more fully understood, reference is had to the accompanying drawings forming a part of this description, showing a preferred embodiment of the 40 invention, in which:

Fig. 1 is a side elevation, partly in section, showing my improved attachment and tile placing means, and its application to a wheel type excavator, omitting the pump and fluid 45 supply means;

Fig. 2 is a view similar to Fig. 1, except that the tile placing means has been retracted and the section exposes one leg of the elevating means for removing water and slush from the attachment;

Fig. 3 is a vertical sectional view, partly in elevation, as the same would appear, if taken on the line 3-3 Fig. 1;

Fig. 4 is a plan view, partly in section, as the same would appear, if taken on the line 55 4-4 Fig. 1;

Fig. 5 is a detail in elevation, partly in section, as the same would appear, if taken on the line 5-5 Fig. 1, and

Fig. 6 is a diagrammatic view of the excavator, showing the frame work and the fluid supply and pressure system for the pneumatic control and operation of the tile placing means.

Like characters of reference denote corresponding parts thruout the figures.

Ditching or excavating machines of the wheeled type are well known to those skilled in the art, and I therefore have only shown so much of such a machine as will be necessary to illustrate the connection of my tile laying attachment thereto. The digging wheel of such machines is designated by the dotted lines 1 provided with the annular toothed rims 2 engaged by driving gear 75 wheels 3, carried on a shaft 4, operated in any suitable manner from the motive power carried by the machine. These machines have a supporting framework, which in this instance is designated by the beams 5, 6 and 7, and it is to these beams that my tile laying attachment, to be described, is suitably connected.

Ordinarily the ditches dug by the ditching or excavating machines, in which the drain tile is laid, is in ground where the danger of a cave-in of the side walls of the ditch is not to be seriously considered, and the tile may be laid by the workmen with little or no difficulty and without the need of such an attachment as herein shown and described. However, ground is often encountered in which the ditches are dug which is very muddy, or which contains considerable quicksand. In either event the laying of the tile during the digging of the ditches or thereafter, is done with considerable difficulty, by reason of the fact, that cave-ins will occur before the tile sections can be properly laid and placed in juxtaposition to each other, and incidents are on record, where, during the laying of the tile sections in such ground, cave-ins have occurred, and the pressure has been so great upon the tile sections that they were separated axially, the ground 100 forcing the tile sections apart and entering

therebetween, destroying communication between the said tile sections. My attachment aims to overcome the possibility of the cave-in of the walls of the ditches during the placing of the tile sections, and makes it possible to so place the said sections in juxtaposition to each other that they are retained in place and cave-ins will have no material effect thereon to separate the same.

10 Further, when ground is encountered containing quicksand, my attachment provides for the introduction of gravel into the ditch on which the tile sections may be laid and for covering and surrounding said tile sections with gravel to protect the same against caving in of the walls of the ditch.

15 The attachment includes a housing made up of the opposite side walls 8, connected by the curved bottom wall 9, the front 20 curved wall 10 and the rear vertical wall 10^a, the latter stopping short at the bottom of the housing as at 11 to provide an opening in the rear end of the housing as shown at the bottom in Figs. 1 and 2, thru which 25 are pushed the tile sections A, as will be more fully explained. The forward ends of the side walls 8 and the front wall 10 are arranged to have a suitable detachable connection with the beams 7 forming a part 30 of the frame work of the machine, whereby the housing is drawn by the machine and thru the ditch cut by the ditching wheel 1. In other words, the housing trails the ditching wheel with the curved bottom 9 of the 35 housing, preferably moving on the bottom of the ditch and conforming to the cross-section thereof, see Figs. 3 and 5. The said housing, as will be observed looking at the cross-sectional views 3 and 5 constitutes a 40 movable curbing to retain the walls of the ditch during the placing of the tile, the tile placing means being operably carried within the housing, as will be explained.

45 The tile placing or pushing means, comprises preferably a carriage 12 mounted on rollers 13 adapted to travel on rails 14 secured to and extending longitudinally of the curved bottom 9 of the housing, said carriage having attached thereto a head 50 plate 15 acting as the placer or pusher for the tile sections, in a manner to be described. Pivotally connected, centrally to and at the forward end of the carriage 12, and preferably immediately in the rear of the plate 15, is a curved bar or rod 16, which at its forward end is pivotally connected to a slightly curved link 17, and said link at its forward end is pivotally connected to the lower end of a piston rod 18, connected 55 to a piston (not shown) reciprocally carried in the cylinder 19. I preferably provide anti-friction rollers 20 and 21, respectively, at the points of connection of the bar or rod 16 with the link 17, and of the link 17 with the piston rod 18, and said

rollers travel between spaced guides 22 and 23 arranged within a housing 24 disposed within the housing attachment and preferably at or near the forward end thereof, an upstanding transverse partition 25 in the main housing constituting a part of the front wall of the housing 24, so that the operative parts of the tile placing and holding means are confined within the housing 24 and within the walls 8, 9, 10^a and 25 70 constituting the main housing, see Fig. 1. The main portion of the housing 24 is arranged in a preferably upstanding position and has a lower curved end opening into the main housing of the attachment. This is true also of the guides 22 and 23 which are confined within the housing 24, and the respective guides 22 and 23 separated to allow for the up and down and angular movement of the bar or rod 16 and the link 17. As shown, the carriage 12 and placer or pusher 15 thereon are adapted to have horizontal movement only, and this movement is imparted thru the bar or rod 16, link 17 and piston rod 18 from means, 75 preferably arranged in an upstanding position in the machine. Therefore, the housing 24 and guides 22 and 23 are so constructed, and the bar or rod 16 and link 17 so designed, that the vertical reciprocal 80 movement imparted to the piston-rod 18 is transformed into a horizontal movement.

85 To the upper end of the cylinder 19 is connected a pipe 26 and to the lower end of said cylinder is connected a pipe 27, both of which connect with a preferably four way valve coupling 28, provided with a valve handle 29. To said valve coupling is also connected a pipe 31. In Fig. 6 the pipe 30 connects direct with a pressure tank 32 90 and a pipe 33 connects the pressure tank with a suitable pump 34. This pump in turn is connected by a pipe 35 with a supply or reservoir tank 36 to which the pipe 31, is connected.

95 I prefer to mount the entire fluid pressure system and its operative parts on the frame-work, including the parts 5, 6 and 7 and any component parts or bracing structures thereof, as this frame carries the excavating wheel and its operating parts and also the tile placing attachment and its parts. The entire frame-work is usually pivoted to the main frame of the excavator at 37 to permit the wheel and the tile placing attachment to be raised and lowered. At 37 I locate a shaft carrying a large bevel gear wheel 38 with which meshes the diametrically opposed driving and driven 100 bevel gear pinions 39 and 40, the former carried on a driving shaft leading to the engine, not shown, or other motive means of the excavator, and the latter carried on a shaft 41 suitably journaled on the frame-work described. The shaft 41 thru suitable 105

110

115

120

125

130

connecting gearing 42 actuates a shaft 43 thru suitable connecting gearing 44 operates the pump 34, see Fig. 6.

The operation of placing a tile by the means described, is as follows:—It is understood of course that the excavator is moved forward a suitable distance, the wheel 1 cutting a ditch and the dirt removed to one side thereof. When the machine has progressed a sufficient distance, a signal is given to the operator and the machine is stopped, the tile placing and holding means being approximately in the position shown in Fig. 2. A tile A is handed the attendant within the main housing who lowers it into position on the bottom 9 between the rails 14. This done, the valve handle 29 is manipulated to permit fluid to flow into the upper end of the cylinder to operate the piston rod 18, link 17, bar or rod 16 and the carriage 12 moving the plate 15 into engagement with the tile A moving it into position and in juxtaposition to a preceding tile section, if one has been placed, and holding the tile section in such position. This position of the parts may be maintained whether the machine is then moved forward or not; it being intended of course to hold the tile after the signal has been given to advance the machine, so as to insure that there shall be no separation of the tile sections. The attendant has full control of the pneumatic pressure means for operating the tile placing means, thru the handle 29 and may reverse the movement of the fluid at will to operate and retract such placing means. The tile as placed are moved out thru the opening 11, at the rear of the housing, it being understood that the tile placing mechanism is not only designed to engage and move the tile sections in to position, one against the other, to provide a complete and perfect drain, but that such mechanism also serves to hold the tile sections, one against the other to prevent loose joints, and that such holding operation continues during the stoppage of the machine and during the forward movement of the machine following each placing operation; thereby obviating any and all danger of the tiles separating.

The attachment, as now described, is useful when the machine is operating in muddy ground void of quicksand conditions, but which is subject to cave-in, the side walls 8 of the housing acting as a curbing to retain the side walls of the ditch and permit the placing of the tile sections A on the bottom of the ditch, the said tile sections being pushed out thru the opening in the rear end of the said housing, as will be understood.

To provide for the laying of the tile sections in ditches where quicksand is encountered, I preferably employ a chute 45 formed with a hopper 46 at its upper end and with a semi-

circular rearwardly extending shield 47 at its lower end. This chute is preferably arranged for detachable connection with the rear end wall of the housing.

To use the chute, it is filled with gravel, represented by the dotted lines in Figs. 1 and 2 which forms a bed on the bottom of the ditch on which the tile is laid and then completely surrounds the tile, so as to protect the latter against the quicksand action and any cave-in of the walls of the ditch. In Fig. 2 a tile section A is shown in place and protruding thru the opening in the rear end of the housing, part of the tile within the housing and part without, but protected by the shield 47 of the chute. Here it will be seen that the gravel has formed a bed for the said section of tile, and covers all of that portion protruding without the housing and has spread within the housing almost to the forward end of the tile section. At this point a new tile section is placed so as to be moved in juxtaposition to the tile section lying part within and part without the housing, and when the new section has been so placed the forward movement of the machine will allow the gravel discharged from the chute to spread over and around the newly placed tile section in the manner shown in connection with the last placed tile section in Fig. 2. It is to be understood that the placing of the said tile sections when using the chute 45 is so timed that a bed of gravel is provided for the said sections, as shown in Fig. 2, so as the machine moves forwardly there can be no tipping of the said tile sections which would dislodge the same and prevent axial alignment of the next and succeeding tile sections.

I have provided for the removal of water and slush from the main housing of the attachment, which may enter the housing thru or around the tile, due to any causes whatsoever. There are conditions of soil, where if no provision is made for the removal of any such water and slush, sooner or later the housing would fill to such a point that placing and laying of the tile would be prevented, and conditions would be such that an attendant or operator could not stay in the housing of the attachment. Such a means, preferably comprises a bucket elevator, including an endless conveying chain 48 having connected thereto, at intervals, buckets or cups 49. Said chain is driven by a sprocket wheel 50 on a shaft 51 and also passes around an idler sprocket wheel 52 on a shaft 53. This elevator is preferably enclosed within the housing 24 discharging therefrom at the upper end thereof thru a discharge spout 54, and said elevator straddles the guides 22 and 23 in a manner seen in Fig. 4, the housing 24 being open at its lower end, as at 55, see Figs. 1 and 2 to permit the ingress of water and slush thereinto.

to be scooped up by the buckets 49, as the elevator is operated. The shaft 51 at the head end of the elevator is connected by suitable gearing 56 to the shaft 43, previously described, to be operated therefrom.

What I claim is:—

1. In combination with ditch digging means, means for placing tile sections in abutting relation in the ditch, power means 10 for operating the placing means and for holding the sections in their said abutting relation, and means for controlling the operation of the power means thereby to govern the pressure exerted by the tile placing

15 means on the sections.

2. In combination with ditch digging means, means for placing tile sections in abutting relation in the ditch, power means for operating the placing means and a 20 manual control for the power means whereby to regulably govern the pressure exerted by the tile placing means on the sections.

3. In combination with ditch digging means, a housing having a closed front end 25 and an opening adjacent the bottom of its rear, tile placing means operable through the opening, vertically disposed guiding means adjacent the front end of the housing and having a rearwardly curved lower end, 30 means movable in the guiding means and in the curved end thereof and connected to the placing means to actuate the latter, and means connected to the upper part of the actuating means to operate same.

35 4. In combination with ditch digging means, a housing having a closed front end and an opening adjacent to the bottom of its rear, tile placing means operable through the opening, vertically disposed guiding 40 means adjacent the front end of the housing and having a rearwardly curved lower end, means movable in the guiding means and in the curved end thereof and connected to the placing means to actuate the latter, 45 means connected to the upper part of the actuating means to operate same, and an endless water and slush elevator having its vertical flights disposed on opposite sides of the vertical guiding means and having its lower part operating beneath the curved 50 lower end of the guiding means.

5. In combination with ditch digging means, means for placing tile sections in abutting relation in the ditch, vertically disposed means for operating the placing 55 means, and a vertical endless water and slush elevator having its flights arranged on opposite sides of the operating means.

6. In combination with ditch digging 60 means, vertical guiding means having a lower curved part, tile placing means ex-

tending in horizontal alinement with the lower end of the curved part, vertically disposed operating means for the placing means, and means connected to the operating means, and to the tile placing means and engaged with the guiding means for actuating the placing means.

7. In a machine of the character described, in combination, means for digging a ditch, 70 a housing connected to trail the digging means within the ditch, means operating through the housing for placing tile sections in abutting positions in said ditch and for holding the said sections in such position 75 as they are placed, and an elevating means for removing water and slush from said housing.

8. In a machine of the character described, in combination, means for digging a ditch, 80 a housing connected to trail said digging means within the ditch, horizontally disposed tile placing means in the bottom of said housing adapted for reciprocal movement, vertically disposed means arranged 85 for reciprocation within said housing for operating said placing means, flexible connections between said operating means and said tile placing means, and a vertically disposed elevating means straddling said operating means adapted to remove water and slush from said housing.

9. An attachment for a ditch digging machine, comprising a housing having an opening at its rear end for the ejection of tile 95 sections, means within the housing for placing tile sections in abutting positions and pushing the same out thru the opening in said housing, means within the housing for operating said placing means, and an elevator arranged within the housing in front of said placing means for removing water and slush therefrom.

10. An attachment for a ditch digging machine, comprising a main housing having an opening at one end for the ejection of tile sections, horizontally arranged tile placing means disposed for reciprocation on the bottom of the housing and provided with tile engaging means, a supplemental housing arranged in a vertical position in said housing and having a curved lower portion opening thereinto, a cylinder arranged within said supplemental housing, fluid pressure connections with said cylinder, a piston rod reciprocally arranged in said cylinder, and flexible connections between said piston rod and said tile placing means and guided by the lower portion of the supplemental housing.

JOHN SOMMER.
